US00D709564S

(12) **United States Design Patent**
Baumann et al.

(10) **Patent No.:** **US D709,564 S**
(45) **Date of Patent:** **** Jul. 22, 2014**

(54) **SUCTION CUP TOY**

(71) Applicant: **Procreate Brands LLC**, Ferndale, WA (US)

(72) Inventors: **Scott Baumann**, Anacortes, WA (US); **Brian Wheeler**, Bellingham, WA (US)

(73) Assignee: **Octoblocs LLC**, Ferndale, WA (US)

(**) Term: **14 Years**

(21) Appl. No.: **29/471,100**

(22) Filed: **Oct. 28, 2013**

(51) LOC (10) Cl. **21-01**

(52) U.S. Cl.

USPC **D21/398; D21/407; D21/498**

(58) **Field of Classification Search**

USPC ..... D21/300-302, 304, 309, 385-389, D21/398-400, 404, 405-407, 436-440, 453, D21/455, 460, 461, 465, 466, 471, 473, 479, D21/483, 493, 498, 503, 561-563, 567, 572, D21/576-661, 681, 682, 694, 707, 714, 787, D21/790, 794, 798, 811, 812; 446/92, 446/46-48, 69, 71-73, 75, 77, 85, 97-101, 446/117, 120, 121, 124, 125, 126, 128, 129, 446/137-139, 177, 182-184, 186, 187, 193, 446/197, 198, 220-226, 268, 320, 321, 324, 446/337-339, 376, 383, 390, 391, 419, 421, 446/431, 437-439, 458, 486, 487, 489; 473/614, 569-576, 579, 580, 588, 589, 473/592, 595, 596, 612, 615; D19/65, 66, D19/71, 86, 90, 91, 95-97; D11/121, 124, D11/125, 127-130, 131, 157, 158, 160, 164, D11/181; D20/10, 12, 16, 17, 19, 21, D20/29-32, 41; D25/126, 128, 130, 133, D25/135; D8/29, 71, 300, 303, 305, 310, D8/315, 318, 349, 354, 373, 376, 378, 379, D8/402, DIG. 1-DIG. 8; D7/590-597, 599,

D7/611, 665, 669, 670, 393, 395, 396; D24/115, 200, 211-215; D28/92, 93; D30/160; D9/600-681, 500-505; D26/1-7, 25, 40, 41; 428/8, 9, 11, 12, 428/28; 119/707-711; 248/683, 688, 206.2, 248/206.3, 206.4, 205.5-205.8, 363

(57) **CLAIM**

The ornamental design for a suction cup toy, as shown and described.

DESCRIPTION

FIG. 1 is an isometric view of a suction cup toy showing our new design;

FIG. 2 is a front view thereof;

FIG. 3 is a right side view thereof;

FIG. 4 is a left side view thereof;

FIG. 5 is a back view thereof;

FIG. 6 is a top view thereof; and,

FIG. 7 is a bottom view thereof.

1 Claim, 2 Drawing Sheets
